CLAIM

The ornamental design for a divider for a pan or tray as shown and described.

DESCRIPTION

1. Divider for a pan or tray

1.1 : Perspective

1.2 : Right

1.3 : Bottom

1.4 : Top

1.5 : Front

1.6 : in use image

The design is related to a divider which is removable; the form of the divider is triangular and each end of the divider is higher than the rest of the divider; the inside part of the triangular shape divider is hollow and there are equally spaced hollow compartments in the hollow inside part of the

(Continued)

divider; reproduction 1.6 is a reference view showing the divider in use, and does not form part of the claimed design.
